UNITED STATES PATENT OFFICE.

HENRY HARRIS PAYZANT, OF EVERETT, WASHINGTON, ASSIGNOR TO MEYERHAEUSER TIMBER COMPANY, OF EVERETT, WASHINGTON, A CORPORATION OF WASHINGTON.

LUMBER-MARKING DEVICE.

Application filed July 14, 1924. Serial No. 725,975.

This invention relates to a device for marking lumber, which is adapted to be attached to the frame of a planer or other mechanism for treating or handling lumber, and to mark the grade as well as the trademark on each piece of lumber as it passes through the finishing machines.

The general object of the present invention is to provide a device which will mark both the end and the face of the lumber with more satisfactory results than can be obtained with devices heretofore used. It is in certain respects an improvement on the marking device disclosed in my former Patent No. 1,491,735, issued to me April 22, 1924.

Among the improvements may be mentioned the slidable mounting of the inking member which avoids the violent hammering action on the face of the inking pad; improved means for mounting the die-carrying member so as to support the weight thereof after the imprint has been made in the end of the lumber, and also serving to disengage the die from the end grain of the wood at the instant that the die carrying member trips, and also preventing the possible smearing of ink along the surface of the lumber.

Means are also provided to take the place of the toggle shown in the aforesaid patent, the improved means providing for an easier action, fewer working parts, and making possible better resistance adjustment. The surface marker also embodies numerous novel features which will be more fully explained in the detailed description which follows.

The preferred form of the invention is illustrated in the accompanying drawings, in which—

Figure 1 is a vertical longitudinal section of the invention.

Figure 2 is a plan view of the working parts with the housing, cover and bracket support shown in section.

Figure 3 is a front elevation of the device.

Figure 4 is a transverse section.

Figure 5 is a central longitudinal vertical section with the cover raised, and showing the parts in the position they occupy after the marking operation has been completed.

Figure 6 is a detail view illustrating the operation of the end marker.

Figure 7 is a detail view showing the surface marker raised out of operative position. 55

Figure 8 is a detail sectional view of the end die, showing the same about to be engaged by the lumber. 60

Figure 9 is a detail sectional view taken axially through the die block of the surface marker.

Figure 10 is a longitudinal section of a modified form using a gang of surface 65 markers.

Figure 11 is a vertical sectional view of the gang marker.

Figure 12 is a horizontal sectional view of the same. 70

The invention comprises an end marker and a surface marker mounted within a suitable housing 15, having a cover 16, which is hinged to a pivot pin 17 at one end of the housing. The housing is formed at one side 75

with runners or shoes 18, mounted for vertical adjustment in corresponding channels 19 formed in a supporting bracket 20, which is bolted or otherwise secured to the frame 21 of a planer or other wood-working machine in connection with which the invention is used. (Figures 1 to 4.) The runners 18

are provided with rearwardly projecting studs 22, which extend through vertical slots 23 formed in the brackets 20, and through eyes 24 of adjusting bolts 25. The eyes of the adjusting bolts are held in spaced relation to the brackets by means of spacing collars 26, while the upper ends of the bolts project upwardly through ears 27 formed on 80

the upper end of the bracket, and their upper ends are threaded and provided with spacing collars 28 and thumb nuts 29 by means of which the housing 15 may be vertically adjusted, so that the marking devices 85

will be at the proper height to correspond with the thickness of the lumber to be marked. The rear ends of the studs 22 are threaded and provided with lock nuts 30, by means of which the bolts 25 and housing 15 90

may be clamped in properly adjusted position to the bracket 20.

As shown in Figures 1 to 5, the pieces of lumber 31 pass from right to left beneath the housing 15, and first come into contact with the surface marker. 105

This marker comprises a type holder or die block 32, carried between a support formed of two cheek

plates 33 and 34, pivotally supported at their front upper ends on a shaft 35, which is mounted in the sides of the housing 15 (Fig. 7). The block 32 is provided with a central bore 36, as shown in Figure 9, having a trunnion 37 secured in one end thereof and journaled in the cheek plate 33, while the opposite end of the bore is rotatably mounted on a stud 38 secured in the cheek 5 plate 34, and spaced from the trunnion 37 by a pin 38^a. A coiled spring 39 surrounds the pin 38^a and has its ends secured in the stud 38 and trunnion 37, respectively, and is so tensioned as to constantly urge the block 32 10 in an anti-clockwise direction, as viewed in Figure 5. The block 32 has a limited oscillatory movement with respect to the cheek plates 33 and 34, which movement is limited by a pin 40, coming into engagement with 15 either one of the notches 41, 42 in the cheek plates.

The block is provided on one side with a shoulder or abutment 43, which, in the normal position of the block extends into the 20 path of the lumber 31, as shown in Figure 1. As the lumber advances and engages this shoulder, the block is oscillated against the action of the spring 39. In rear of the shoulder 43, the block is formed with a 25 cylindrical surface 44, within which is formed a milled groove for receiving type or dies 45, which are adapted to print upon the surface of the lumber the desired marking as the lumber passes beneath the same. 30 As the lumber advances, its front end in engagement with the shoulder 43, causes the block 32 to oscillate until the type or die 45 makes its impression upon the face of the lumber, and until the flat surface 46 of the 35 block comes in contact with the face of the lumber. The entire block 32 is constantly urged downwardly, and since the radial distance of the flat surface 46 is less than the radial distance of the cylindrical surface 44 from the axis of the block, the flat surface 46 remains in contact with the face of the lumber until the latter has passed. The 40 type or die 45 forms a clear impression upon the face of the lumber, in the same manner as a cylinder press prints a sheet of paper.

The means for urging the block 32 downwardly comprises a shaft 47, having its ends journaled in the cheek plates 33 and 34, and having a pin 48 secured midway of its ends 45 and extending upwardly through a shaft 49, which is journaled in the sides of the housing 15. (Figs. 1 and 5.) An expansile coiled spring 50 surrounds the pin between the shafts 47 and 49 to urge the cheek plates 50 and block 32 downwardly about the shaft 35 as a center. Ink is provided by a roller 51, with which the type or die 45 comes in contact after each operation. The roller 51 is journaled in the free ends of arms 52, 60 which are fulcrumed on the shaft 47. A

shaft 53 extends between the arms 52, and is provided with a laterally extending pin 54, which passes through a shaft 55 journaled in cheek plates 33, 34, and is surrounded by a coiled spring 56, which constantly urges the 70 ink pad into contact with the block 32, in the same manner as the block 32 is urged into contact with the lumber by the spring 50.

The surface marker may at any time be 75 thrown entirely out of operation, as shown in Figure 7, by means of a yoke 57, which is fulcrumed at its lower end on the shaft 49, and connected by links 58 to the shaft 47. The links 58 are made angular, so that they 80 may pass around the shaft 49 and permit the yoke 57 to be swung past dead center to lock the marker in its retracted position out of the path of the lumber.

In passing through the machine, the lumber first comes in contact with the surface marker above described, and then passes along to the end marker which comprises a die carrier or member 59, which is substantially in the shape of a sector, mounted for 85 oscillation on a transverse shaft 60 secured in the sides of the housing 15. The lower front edge of the carrier 59 is formed with a transverse slot 61 adapted to receive a die 62, which is normally disposed in position 90 to form an impression upon the end of the piece of lumber as it passes through the machine. The die 62 is formed with rearwardly disposed ears 63 which extend upon 95 opposite sides of the carrier 59, and are secured thereto by means of a pin or bolt 64. (Fig. 8). A pair of arms 65 are also journaled on the shaft 60 and normally depend therefrom on opposite sides of the carrier 59. (Figs. 1 and 6). These arms also have 100 rearwardly extending projections 66 on the upper rear edges of which rests a plate 67, which extends across the upper edge of the sector shaped carrier 59, and which is adapted to seat in a slot 68 formed 105 in the upper edge of the carrier. An upstanding stud 69 is tapped into the carrier 59 centrally of the slot 68 and extends upwardly through the plate 67, and is surrounded by an expansile coiled spring 70, 110 which bears against the plate 67 and normally holds the arms 65 in their lowermost position, the tension of the spring 70 being adjusted by means of a nut 71 threaded onto the projecting end of the stud. In this position, the lower front edges 72 of the arms 65 are held somewhat in advance of the front surface of the die 62. (Fig. 1). The arms 65 are connected by a pin 73, which passes 115 through a hole 74 in the carrier 59, the hole being somewhat larger than the pin, so that the latter while holding the assembly together permits a limited oscillatory movement of the arms with respect to the carrier 59, so as to uncover the die when the end of 120

the lumber comes into engagement with the front edges 72 of the arms. The lower ends of the arms 65 serve as shoes to carry the weight of the end marking mechanism after 5 the imprint has been made in the end of the lumber, and also serve to disengage the die from the end of the lumber at the instant that the die carrier is tripped. These arms also prevent any possibility of smearing ink 10 along the surface of the lumber, and even if the die itself becomes smeared with ink, the lower ends of the arms, which ride on the surface of the lumber, are always clean. The arms 65 with the die carrier 59 form co- 15 axially mounted elements, one of which projects forwardly at the lower end to contact with the moving lumber, and after such initial contact, the die is engaged with the end of the lumber, this action being brought 20 about by the pin and slotted connection (73, 74) between said elements.

Ink is supplied to the die 62 by means of an inking member 75, having at its lower 25 end a seat for receiving a pad 76, and provided near its upper end with a removable plug 77 for introducing ink. The inking member 75 is adapted to slide longitudinally upon a bar 78, which extends across the bottom of the housing 15, and upon which the member 75 rests. The upper end of the inking member 75 is pivotally connected at 79 to the lever arm 80, which is fulcrumed on a 30 shaft 81, and has a depending weighted trip finger 82, which is normally held by gravity 35 in the path of the advancing lumber. In this position, the pad 76 is in engagement with the die 62, and the trip finger rests against an abutment bar 83 secured to the sides of the housing. As the piece of lumber 31 advances in the direction of the arrow in Figure 1 past the surface marker, it engages the 40 finger 82, swinging it to the left and retracting the inking member 75 into the housing, and leaving the freshly inked die 62 in the path of the end of the lumber. 45

Sufficient resistance is provided to the movement of the carrier 59, so that a clear imprint will be made upon the end of the lumber. The resistance member includes a 50 weight 84 pivoted at its rear end on the shaft 17, and having a wear plate 85 secured to its front face and provided with a lower beveled edge 86, which is normally engaged by the end of a pawl 87 mounted on the carrier 59. (Figs. 1, 5 and 6.) This pawl is provided with a pair of ears 88 disposed on opposite sides of the carrier 59, and pivotally connected thereto by a pivot pin 89, surrounded by a coiled spring 90 which normally urges the pawl into engagement with the beveled edge 86. The weight 84 is provided with a bore 91 into which projects a stud bolt 92, which is secured in the bottom 93 of the housing. An expandable coiled spring 94 surrounds the bolt 92,

and is seated between a shoulder 95, formed at the lower end of the bore 91, and a nut 96 threaded on the end of the bolt, and by means of which the tension of the spring may be adjusted. The resistance member 70 is thus actuated by gravity and by a spring.

As the lumber advances from the position shown in Figure 6, the die carrier 59 is swung upwardly, as shown in dotted lines, against the resistance furnished by the 75 weight of the member 84, and by the tension of the spring 94. As the carrier 59 and weight 84 continue to swing upwardly in opposite directions about their axes, the pawl 87 rides from beneath the wear plate 85 and permits the weight 84 to drop back to its normal position, while the lower ends 72 of the arms 65 ride along the upper surface of the lumber, as shown in Figure 5. In this manner, the die 62 is disengaged from the 80 end of the lumber without smearing, and is held out of contact with the lumber until the latter passes out of the machine. The carrier 59 then drops back to its original 85 position, the spring 90 yielding sufficiently 90 to permit the pawl to pass the wear plate 85, and again become engaged with the beveled edge 86.

By using the weight 84 and the pressure 95 spring 94, a simple arrangement is provided for impressing the die 62 against the lumber, which is easy in its action, and is capable of precise adjustment. The arms 65, with their limited movement with respect to the carrier 59, serve to disengage the die instantaneously from the end of the lumber at the moment that the pawl 87 leaves the beveled edge 86 of the pressure member. The ends 100 72 of the arms serve as shoes to carry the weight of the end marking member, and serve effectively to prevent any smearing of the surface of the lumber as the latter passes on beneath the marker. The surface marker is also capable of the finest adjustment, and the parts which come in contact with the inking roller are effectively prevented from being dragged over the surface of the lumber and smearing the same.

In using the marker, as herein described, 110 it is proposed to use the end marker for imprinting the trade-mark, while the surface marker will mark the grade. A plurality of surface markers will, therefore, ordinarily be provided corresponding to the different grades, and arranged so that any 115 one of them may be operated, while the others are inoperative. These several surface markers may be arranged in tandem relation within the housing 15, which will be made long enough for this purpose, or a plurality of them may be arranged in the manner shown in Figures 10, 11 and 12. In the latter arrangement, a plurality of marking devices 97 are shown supported for rocking 120 movement between circular plates 98, and 125 130

with each marking device a spring-held inking roller 99 cooperates. Each marking device 97 is provided with a pin 100, which cooperates with the respective notches 101 in the corresponding plate 98 to limit the movement of the marking device, in the same manner as the surface marking device shown in Figures 1 to 9. The plates 98 are mounted for angular adjustment about a resiliently supported shaft 102, and a locking pin 103 is provided, which may be inserted through holes 104 in the sides of the housing 15, and in the holes 105 of the respective plates 98, which correspond to the marker which it is desired to use. Thus, the plates 98 may be adjusted so that the desired marker is brought into proper position for operation, while all of the other surface markers are in inoperative position 20 out of the path of the lumber.

While I have shown and described the specific structure of what is at present the preferred form of the invention, it is to be understood that this is merely illustrative, 25 and that many modifications may be made in the structure and relation of the various parts without departing from the scope of the invention or sacrificing any of its advantages.

30 What is claimed is:—

1. A marking device, comprising, in combination, a housing, a member pivoted within the housing, a die carried by said member and normally depending beneath the housing, a bar extending transversely of the housing in front of the die, and an inking member resting on said bar and 25 slidable across the same into and out of contact with the die.

40 2. A marking device, comprising, in combination, a movable die member, a slidably mounted inking member arranged in advance of and at an inclination to the die member and normally in contact with the die of said member, and a trip finger pivotally connected to said inking member and arranged to be engaged by the article to be marked.

50 3. A marking device, comprising, in combination, a movable die member, an inking member arranged in advance of the die member, means for mounting said inking member independently of said die member, said inking member normally contacting with the die member, and a tripping device 55 connected to said inking member to be actuated by the article to be marked so as to move the inking member out of contact with the die member.

60 4. A marking device, comprising, in combination, a movable die member carrying a marking die, an inking member arranged in advance of the die member and mounted independently thereof, said inking member delivering ink to the die of said die mem-

ber, a lever arm pivoted to said inking member, and a trip finger depending from said lever arm.

5. A marking device, comprising, in combination, a pivoted member, a die carried thereby, a slidable inking member normally in contact with the die, a support on which the inking member rests, and a lever arm pivotally connected with the inking member and rockable to retract the same. 75

6. In a marking device for lumber and the like, the combination of a housing, a member pivoted within and depending from the housing, a die carried by said pivoted member in the path of the lumber, a downwardly inclined inking member slidably resting on a part of the housing with its lower end normally in contact with the die, and an arm pivoted in the housing and pivotally connected with the inking member, 80 said arm having means engageable by the lumber to rock the arm and retract the inking member. 85

7. A device for marking lumber and the like, comprising, in combination, a housing, 90 a member pivoted within the housing, a die carried by said member and normally depending in the path of lumber passing beneath the housing, a bar extending transversely of the housing in front of the die, an inking member resting on said bar and slidable across the same into and out of contact with said die, and means for bodily adjusting the housing vertically to adapt it to the thickness of the lumber. 95

8. A device for marking lumber and the like, comprising, in combination, a housing, a member mounted within the housing and operable by a piece of lumber passing beneath the housing to mark the surface of the same, a second marker mounted in rear of the first marker and independently thereof and including a die depending in the path of the lumber to mark the end thereof, 105 and means for bodily adjusting the housing vertically to adapt it to the thickness of the lumber. 110

9. A device for marking lumber and the like, comprising, in combination, a housing, 115 a member mounted within the housing and operable by a piece of lumber passing beneath the housing to mark the surface of the same, a second marker mounted in rear of the first marker and including a die depending in the path of the lumber to mark the end thereof, a slidably mounted inking member reciprocable into and out of contact with said die, and a tripping member depending into the path of the lumber and operable thereby to retract the inking member. 120

10. In a marking device for lumber and the like, the combination of a pivoted die carrier, a die secured thereto with its face in the path of the lumber, a pair of arms 125

5 pivoted on the same axis as the carrier and disposed on opposite sides thereof with their front edges normally in advance of the face of the die, and movable about their axes independently of the carrier by the advancing lumber to permit the latter to be impressed by the die.

10 11. In a marking device for lumber and the like, the combination of a pivoted die carrier, a die secured thereto with its face disposed in the path of the lumber, a pair of arms pivoted on the same axis as the carrier and disposed on opposite sides thereof, said arms having a limited movement about their axes independent of its carrier, means normally holding the arms with their front edges in advance of the face of the die, but yieldable when their front edges are engaged by the advancing lumber to permit the latter 20 to come into contact with the face of the die.

12. In a marking device for moving lumber, the combination of a pivoted carrier, a die secured thereto, with its face disposed 25 in the path of the moving lumber, and a separate element pivoted coaxially and having arms depending below the die carrier and serving as shoes to carry the weight of the mechanism after the imprint has been made 30 on the lumber.

13. In a marking device for moving lumber, the combination of a pivoted member, a die secured thereto with its face in the path of the moving lumber, and means associated 35 with said member and adapted to contact with the lumber in advance of the die, said means acting independently of said member.

14. In a marking device for moving lumber, the combination of a pivoted member, a die secured thereto with its face in the path of the moving lumber, and means associated 40 with said member and acting independently thereof to contact with the lumber in advance of the die, and then disengage the die from the end of the lumber and thereafter carry the weight of the marking mechanism.

15. In a marking device for moving lumber, the combination of a pivoted member, a die secured thereto and having its operative face in the path of the moving lumber, 45 and a separate element associated with said member, spring-actuated means connecting said member and said element, and a pin and slot connection between said member and said element.

16. A marking device for moving lumber, comprising two movable elements having a common pivot and arranged in associated relation, a die carried by one of said 50 elements in the path of moving lumber, means for projecting the other of said elements in advance of that element carrying the die, and means for connecting said elements to cause the said other element to disengage the die from the end of the lumber 65

and thereafter carry the weight of the marking mechanism.

17. In a marking device for moving lumber, the combination with a pivoted carrier member having a die secured to its front extremity, a protective member pivoted on the same axis as the carrier member and acting independently thereof to contact with the lumber in advance of the carrier member, yieldable means normally holding the protective member with its front face in advance of the face of the die, and means positively limiting the angle of relative displacement of the two members in either direction, so that the die contacts with the lumber after the initial contact by the protective member. 70 75 80

18. In a marking device for lumber and the like, the combination of a pivoted die carrier, a die secured thereto with its face disposed in the path of the lumber, a pair of arms pivoted on the same axis as the carrier and disposed on opposite sides thereof, said arms having a limited movement about their axes independent of the carrier, means normally holding the arms with their front edges in advance of the face of the die, but yieldable when their front edges are engaged by the advancing lumber to permit the latter to come into contact with the face of the die, and yieldable means holding the die carrier against movement and offering greater resistance than the first-mentioned yieldable means whereby the lumber will be impressed by the die. 95 100

19. In a marking device for moving lumber, the combination of a movable member, a die carried thereby in the path of the moving lumber, an engaging element on said member, a resistance member movable away from the die carrying member and normally in the path of movement of said engaging element, and means whereby the element on said die carrying member may be caused to engage with and become disengaged from the resistance member. 105 110

20. In a marking device for lumber and the like, the combination of a pivoted carrier member, a die carried thereby in the path of the lumber, a resistance member having a portion engageable with the carrier member to resist movement of the latter as it is engaged by the lumber, said resistance member being pivoted to swing in the opposite direction about its axis away from the carrier member to release the latter after a predetermined movement. 115 120

21. In a marking device for lumber and the like, the combination of a depending pivoted carrier member, a die carried thereby in the path of the lumber, a combined spring and gravity resistance member having a portion engageable with the carrier member to resist movement of the latter as it is engaged and swung upwardly by the 125 130

lumber, said resistance member being pivoted to swing upwardly in the opposite direction about its axis away from the carrier member to release the latter and allow it to drop after a predetermined movement thereof.

22. In a marking device for lumber and the like, the combination of a pivoted carrier member, a die carried thereby in the path of the lumber, a pair of arms pivoted on the same axis as the carrier member and disposed on opposite sides thereof, with their front faces normally in advance of the face of the die and movable about their axes independent of the carrier by the advance of the lumber to permit the latter to be impressed by the die, a resistance member having a portion engageable with the carrier member to resist movement of the latter as it is engaged by the lumber, said resistance member being pivoted to swing in the opposite direction about its axis away from the carrier member to release the latter after a predetermined movement.

23. In a marking device for lumber, the combination of a pivoted die member, a resistance member movable in an opposite direction from the die member, and a pawl on the die member to engage the resistance member.

24. In a marking device for lumber and the like, the combination of a pivoted carrier member, a die carried thereby in the path of the lumber, a spring-held pawl mounted on the carrier member, a resistance member having a shoulder which the pawl normally engages to resist pivotal upward movement of the carrier as it is engaged by the lumber, said resistance member being pivoted to swing away from the pawl as the resistance member is moved upwardly by the pawl until the pawl rides from beneath the shoulder and permits the resistance member to drop back to its original position, the spring of the pawl permitting the latter to pass the shoulder when the lumber passes from beneath the carrier member and permits the latter to drop.

25. In a marking device for lumber and the like, the combination of a pivoted carrier member, a die carried thereby in the path of the lumber, a pair of arms pivoted on the same axis as the carrier member and disposed on opposite sides thereof with their front edges normally in advance of the face of the die and movable about their axes independently of the carrier member by the advancing lumber to permit the latter to be impressed by the die, a spring-held pawl mounted on the carrier member, a resistance member having a shoulder which the pawl normally engages to resist the pivotal upward movement of the carrier as it is engaged by the lumber, said resistance member being pivoted to swing away from the

pawl as said members are moved upwardly until the pawl rides from beneath the shoulder and permits the resistance member to drop back to its original position, the spring of the pawl permitting the pawl to pass the shoulder when the lumber passes from beneath the carrier member and permits the latter to drop.

26. In a marking device the combination of a pair of pivotally mounted cheek plates, means positively limiting their movement in one direction about their pivots, yieldable means resisting their movement in the other direction, a marking element mounted for rocking movement in the free ends of said plates, means for positively limiting the rocking movement of said element in either direction, yieldable means normally holding the marking element at one limit of its rocking movement, and means engageable by a piece of lumber passing therebeneath to rock said element in the opposite direction to bring its face into engagement with the lumber to mark the same.

27. In a marking device, the combination of a marking element supported for rocking movement, means for positively limiting its rocking movement in either direction, yieldable means normally holding the marking element at one limit of its rocking movement, and means engageable by a piece of lumber passing therebeneath to rock said element in the opposite direction to bring its face into engagement with the lumber to mark the same.

28. In a marking device, the combination with a support, a marking element mounted in the support for oscillatory movement and carrying a die block, resilient means for constantly urging the element in one direction, means for limiting the oscillatory movement of the block in either one of two directions, an abutment on the block to be engaged by the lumber to be marked, and an inking roller mounted in the support and adapted to contact with the die on said block.

29. In a marking device, the combination of a pair of cheek plates pivotally mounted, means for limiting the movement of the cheek plates in one direction, a marking element mounted for oscillatory movement in the cheek plates and carrying a die, a resilient means for urging the said element in one direction, means for limiting the oscillatory movement of the marking element in either one of two directions, an abutment on said element, and an inking device including an ink pad having means for constantly urging the ink pad into contact with the die of said marking element.

30. In a marking device for moving lumber, the combination of a support, a marking element mounted in the support for limited oscillatory movement and said mark-

ing element being provided with an abutment to be engaged by the lumber and in rear of the abutment formed with a cylindrical surface for receiving a marking die, and a flat surface, means for urging the marking element outwardly, and an inking roller having means for urging the same into contact with the marking die.

31. In a marking device for moving lumber, the combination of a housing, a pair of cheek plates pivotally mounted in the housing, a marking element mounted in the cheek plates for limited oscillatory movement and carrying a marking die, an abutment on said marking element to be engaged by the moving lumber, a shaft journaled in the cheek plates, an inking roller mounted on arms fulcrumed on said shaft, and a spring for urging the arms carrying the inking roller into contact with the marking die.

32. In a marking device, the combination of a housing, a pair of cheek plates, a shaft pivotally supporting the cheek plates, a marking element mounted in said cheek plates for oscillatory movement and provided with an abutment and a marking die, means for constantly urging the marking element in one direction, means for limiting the movement of said marking element, a shaft mounted in the cheek plates, an inking device mounted on said shaft and having its ink pad in engagement with the marking die, and means connected to the cheek plates for moving the marking element within the housing.

33. In a marking device for moving lumber, the combination of a housing, a marking mechanism pivotally mounted within the housing and carrying the marking ele-

ment, said marking element normally projecting from the housing in the path of the moving lumber, and means on said marking mechanism for moving the same within the housing and maintaining it in fixed position.

34. A marking device comprising a shaft, a pair of plates mounted thereon, a die block journaled between said plates and having an abutment and a cylindrical printing surface in rear of said abutment, said block having a limited oscillatory movement with respect to said plates, an inking roller, and spring means for constantly urging said roller in contact with the said block.

35. A marking device comprising a shaft, a pair of plates mounted thereon, a die block journaled between said plates and having an abutment and a cylindrical printing surface in rear of said abutment, said block carrying a pin to engage notches in one of said plates to limit the oscillatory movement of said block, an inking roller, and spring means for constantly urging said roller in contact with the said block.

36. In a marking device for lumber and the like, the combination of a marker supported for rocking movement and having means operable by lumber passing beneath the same to mark the face of the lumber, a second marker mounted in rear of the first marker and including a die depending in the path of the lumber to mark the end thereof, and means for securing one of said markers out of operative position independently of the other.

In testimony, that I claim the foregoing as my own, I have hereto affixed my signature.

HENRY HARRIS PAYZANT.
